REMOVAL OF WAX FROM HYDROCARBON OIL

Robert E. Manley, Bernard Y. McCarty, and Howard H. Gross, Beacon, N. Y., assignors to The Texas Company, New York, N. Y., a corporation of Delaware

Application August 22, 1933, Serial No. 686,244

13 Claims. (Cl. 196—19)

This invention relates to the removal of wax from hydrocarbon oil, and more particularly to dewaxing mineral lubricating oil.

The invention broadly contemplates a process for removing wax from wax-bearing hydrocarbon oil wherein the wax-bearing oil is treated with a relatively small amount of a carbonaceous material derived from cracked petroleum tar, and which is adapted to modify wax crystal formation and thereby facilitate separation of the wax from the oil. The wax-bearing mixture is then diluted with a suitable solvent, such as petroleum naphtha, and chilled to precipitate the wax. The wax thus precipitated is removed by mechanical means, or by cold settling, following which the diluent is removed from the resulting dewaxed oil.

In the drawing, the single figure is a flow sheet of the process of the present invention.

We have discovered that cracking still residue or the tar resulting from the cracking of petroleum oil for the production of motor fuel, when subjected to further decomposition or re-cracking, contains certain constituents which are adapted to facilitate the removal of wax constituents from mineral lubricating oil, when added thereto in relatively small proportions. Cracked pressure tar herein described is that produced according to the method disclosed and claimed in the co-pending application of R. E. Manley and H. H. Gross, Serial No. 658,668, filed February 25, 1933, and wherein the addition of this material as a concentrated pour point depressant to a lubricating oil is described and claimed.

The addition of this material to a wax-bearing solution modifies the growth of the wax crystals precipitated from the solution upon chilling. It appears to inhibit the precipitation of wax in the form of a network of interlocking needle crystals as is the normal tendency upon precipitation from cold solution. Instead the wax tends to be precipitated in discrete particle form. The presence of this modifying material thus results in the formation of a crystal mass of wax which is more readily removed from the oil by cold settling.

We have found that cracked petroleum tar may be converted to a pitch, representing about 50% or 60% of the original tar, which will contain substantial amounts of the desired constituents. The method of conversion comprises subjecting the tar resulting from the ordinary cracking operation to further cracking at temperatures of about 800° to around 1000° F., and under pres-

sures which may range from substantially above atmospheric to around 400 pounds or higher.

The particular conditions of temperature and pressure, however, may be varied, depending upon the nature of the tar and, to some extent, upon the yield and nature of the products desired. Thus, it has been found that the cracked tars resulting from the cracking of mineral oil derived from different crude petroleum sources require somewhat different treating conditions to convert them into a pitch containing the desired constituents.

Referring to the drawing, the pitch 10 thus produced by the conversion of cracked petroleum tars is then advantageously mixed in extractor 15 and agitator 11 with a suitable quantity of a relatively viscous mineral oil 12 such as a lubricating fraction, for example, in the proportions of about one part of pitch to one part of oil. This mixture is then subjected to heating for about thirty minutes at a temperature of around 320° F. in the presence of a comminuted solid catalytic material 13, such as a diatomaceous earth, fuller's earth, or acid-treated clay, for example. The temperature of this treatment may vary from around 300° to 400° F. and the treatment may, if desired, be carried out in the presence of steam.

The resulting mixture of liquid and solid catalytic material, while hot, is subjected to filtration in filter 14 to remove the solid matter and produce a filtrate 15 of oil and dissolved constituents which have been extracted from the pitch, and thus separated from the undissolved solids 16. This filtrate solution comprises the wax crystal modifying material in solution and adapted to be added to wax-bearing oil to facilitate the removal of wax therefrom.

This modifying material recovered from the converted cracked tar, dissolved in the solvent oil, may be added to wax-bearing oil 17 which is to be dewaxed by filtration, centrifuging, cold settling, or by other methods. The presence of this material in the wax-bearing mixture results in very greatly increasing filtering rates, or in materially improving the degree of wax separation by cold settling. It materially reduces the dewaxing losses by improving the degree of separation realized between the oil constituents and the wax constituents of the wax-bearing mixture. This is further illustrated by reference to the following examples:

A quantity of the foregoing solution of modifying material in mineral oil was added to a cylinder stock distillate having a viscosity of about 73 Saybolt Universal seconds at 210° F., the pro-

portion of modifying solution comprising about 6% by volume of the wax-bearing distillate. This mixture was then diluted with a light petroleum naphtha from dewaxing solvent tank 18 in the proportion of about four parts of naphtha to one part of wax-bearing mixture.

The resulting solution was then cooled in chiller 19 to a temperature of around -20° to -25° F. and subjected to settling at these temperatures.

10 Settling of the wax constituents from the mixture rapidly occurred. The supernatant liquid layer of oil and solvent was drawn off, and the solvent removed therefrom by distillation. The resulting oil had a pour test of 0° F. The dewaxing loss, as represented by the lower layer composed of waxy constituents settled out of the oil, constituted about 41% of the original wax-bearing oil.

20 When subjecting a mixture of the same wax-bearing oil with the same proportion of light petroleum naphtha to settling but without the addition of the modifying material from the cracked petroleum tar, a substantially smaller yield of oil having the same pour test was produced; that is to say, the dewaxing loss in this instance constituted about 53% of the original wax-bearing oil.

25 This same wax-bearing stock, when mixed with substantially the same proportion of the constituents recovered from the tar, and when diluted in substantially the same proportion of light petroleum naphtha, was subjected to dewaxing by pressure filtration in filter 20 in the presence of a filter-aid material. It was found that the 30 filtering rates of this mixture were increased several times over that obtaining when filtering a similar wax-bearing mixture but which did not contain the modifying material. The filtrate separated from the solids including wax 21 is passed to distillation equipment 22, where retained solvent 23 is removed from the dewaxed oil 24.

35 While certain temperature and pressure conditions, as well as liquid proportions, have been set forth in the foregoing examples, the invention is not restricted to these particular conditions since they may be varied as desired, depending upon the nature of the wax-bearing oil undergoing treatment and upon the extent of the dewaxing required.

40 While we have described extracting a modifying material of desired characteristics from converted cracked petroleum tar by treatment with a lubricating oil fraction of mineral oil, it is contemplated that, in many instances, other fractions of mineral oil or solvents, capable of extracting these constituents from the pitch may be used. It is contemplated also that the converted tar or pitch may be added directly to the 45 wax-bearing oil, or a portion thereof, and the resulting mixture subjected to digestion for a short interval of time at temperatures of around 320° or 350° F., either with or without the presence of clay, in order to extract the desired constituents, and thus avoid the use of an intermediate extracting solvent. Where a portion only is treated, it may then be added to the main body of wax-bearing oil and thoroughly mixed therewith. The resulting mixture, after dilution with naphtha or other diluent or solvent, 50 may be cooled and chilled to the desired dewaxing temperature in order to precipitate the wax. The wax constituents will be precipitated and separated from the oil along with the insoluble portions of the extracted modifying material. In 55 this way, the combined procedure of recovering

the desired modifying material from the converted tar, its addition to the wax-bearing oil, and the subsequent removal of the wax, is simplified.

60 It is also contemplated that other diluents besides naphtha may be employed in the dewaxing step, such as mixtures of acetone and benzol, or mixtures of other selective and non-selective solvent liquids which are capable of serving as satisfactory dewaxing solvent.

65 Obviously many modifications and variations of the invention, as hereinbefore set forth, may be made without departing from the spirit and scope thereof, and therefore only such limitations should be imposed as are indicated in the appended claims.

70 We claim—

1. The method of separating wax from wax-bearing oil comprising mixing with the oil a hydrocarbon material of limited solubility in the oil derived from recracked cracked petroleum tar and containing oil soluble constituents adapted to modify wax crystal formation to thereby facilitate removal of the wax from the oil, adding a diluent to the oil in sufficient proportions to produce a relatively non-viscous mixture at low temperatures, chilling the resulting mixture to precipitate the wax, removing the wax thus precipitated, and recovering the diluent from the dewaxed oil.

75 2. The method of separating wax from wax-bearing oil comprising mixing with the oil a hydrocarbon material derived from recracked cracked petroleum tar and containing oil soluble constituents adapted to modify wax crystal formation to thereby facilitate removal of the wax from the oil, other constituents of the material being substantially insoluble in the oil, diluting the oil by the addition thereto of a substantial proportion of light petroleum naphtha, chilling the resulting mixture to precipitate the wax, removing the wax thus precipitated, and recovering the diluent from the dewaxed oil.

80 3. The method of separating wax from wax-bearing oil comprising mixing said filtrate liquid with the wax-bearing oil, a filtrate obtained from contact filtration at elevated temperature in the presence of a comminuted adsorbent material of a mineral lubricating oil mixture with a pitch derived from recracked cracked petroleum tar and of limited solubility in the oil, the filtrate being mixed in the proportion of about 5% to 10% of filtrate by volume of the wax-bearing oil, diluting said mixture to facilitate subsequent removal of the wax, chilling the resulting mixture to precipitate the wax, removing the wax thus precipitated, and recovering the diluent from the dewaxed oil.

85 4. The method of separating wax from wax-bearing oil comprising mixing the wax-bearing oil with a suitable proportion of pitch of limited solubility in the oil produced by subjecting cracked petroleum tar to additional cracking, subjecting said mixture to digestion at elevated temperature to extract from the pitch constituents adapted to precipitate wax from cold solution in a readily separable form, diluting the digested mixture to facilitate subsequent removal of the wax, chilling the resulting mixture to precipitate the wax, removing the wax thus precipitated, and recovering the diluent from the dewaxed oil.

90 5. The method of separating wax from wax-bearing oil comprising mixing a portion of the wax-bearing oil with about an equal volume of

- pitch produced by subjecting cracked petroleum tar to additional cracking such as to concentrate oil soluble constituents adapted to modify wax crystal formation and render other constituents substantially oil insoluble, subjecting said mixture to digestion at elevated temperature to extract from the pitch constituents adapted to precipitate wax from cold solution in a readily separable form, mixing the digested oil with the main body of wax-bearing oil, diluting the digested mixture to facilitate subsequent removal of the wax, chilling the resulting mixture to precipitate the wax, removing the wax thus precipitated, and recovering the diluent from the dewaxed oil. 5
6. The method of dewaxing a wax bearing oil, comprising mixing with the oil a small proportion of a concentrated pour point depressant material derived from a recracked pressure tar which is primarily insoluble in the oil but which contains oil soluble pour depressant material which has the property of materially increasing the rate of filtration of an oil containing wax precipitated in the presence of the pour point depressant material, chilling the mixture to precipitate the wax, and then filtering to remove the precipitated wax from the oil. 10
7. The method of dewaxing a wax bearing oil, comprising mixing with the oil a concentrated pour point depressant material derived from a recracked pressure tar which is primarily insoluble in the oil but which contains oil soluble pour depressant material, the latter having the property of increasing the rate of filtration of an oil containing wax precipitated in the presence of the pour point depressant material, chilling the mixture to precipitate the wax, and then filtering in the presence of a filter-aid material to remove the precipitated wax and filter-aid material from the oil. 15
8. The method of dewaxing a wax bearing oil, comprising mixing with the oil a solvent highly selective between the normally liquid and normally solid constituents of the oil and in which the normally liquid constituents are soluble at lowered temperatures while the normally solid constituents are substantially completely insoluble, together with a pour point depressant material derived from a recracked pressure tar which is primarily insoluble in the oil but which contains oil soluble pour depressant material which has the property of increasing the rate of filtration of an oil containing wax precipitated in the presence of such a selective solvent and the pour point depressant material, chilling the mixture to precipitate the wax, filtering to remove the precipitated wax, and recovering the solvent from the filtrate. 20
9. The method of dewaxing a wax bearing oil, comprising mixing with the oil a solvent mixture highly selective between normally liquid and normally solid constituents of the oil and having substantially the highly selective solvent action of a mixture of acetone and benzol, together with a pour point depressant material derived from a recracked pressure tar which is primarily insoluble in the oil but which contains oil soluble pour depressant material which has the property of increasing the rate of filtration of an oil containing wax precipitated in the presence of such a selective solvent mixture and the pour point depressant material, chilling the mixture to precipitate the wax, filtering to remove the precipitated wax, and recovering the solvent from the filtrate. 25
10. The method of dewaxing a wax bearing oil, comprising mixing with the oil a solvent mixture comprising acetone and benzol, together with a wax crystal modifying material derived from a recracked pressure tar which is primarily insoluble in the oil but which contains oil soluble pour depressant material and which has the property of increasing the rate of filtration of an oil containing wax precipitated in the presence of such solvent mixture and the modifying material, chilling the mixture to precipitate the wax, filtering to remove the precipitated wax from the oil-solvent liquid, and recovering the acetone and benzol from the filtrate. 30
11. The method of dewaxing a wax bearing oil, comprising mixing with the oil a mineral lubricating oil extract which is concentrated in pour point depressant material derived from a recracked pressure tar which is primarily insoluble in the oil but which contains oil soluble pour depressant material having the property of increasing the rate of filtration of an oil containing wax precipitated in the presence of the pour point depressant material, chilling the mixture to precipitate the wax, and filtering to remove the precipitated wax from the oil. 35
12. The method of dewaxing a wax bearing oil, comprising mixing with the oil a solvent extract of recracked cracking still residue of limited solubility in the oil, the extract being concentrated in oil soluble wax crystal modifying material having the property of increasing the rate of filtration of an oil containing wax precipitated in the presence of such material, chilling the mixture to precipitate the wax, and filtering to remove the precipitated wax from the oil. 40
13. The method of dewaxing a wax bearing oil, comprising mixing with the oil a mineral lubricating oil extract of a pitch derived from recracking pressure tar of limited solubility in the oil, the extract containing a high concentration of oil soluble wax crystal modifying material having the property of increasing the rate of filtration of an oil containing wax precipitated in the presence of such material, chilling the mixture to precipitate the wax, and filtering to remove the precipitated wax from the oil. 45
